VARIABLE HEAT CONTROL ELECTRIC
HAND TOOL

Eustace V. Paolicelli, Corona, N. Y.

Application October 21, 1935, Serial No. 45,865

5 Claims. (Cl. 219—21)

This invention relates to improvements in electrically heated tools, and particularly to an electrical heater tool for applying and working shellac and similar preparations for finishing furniture, and one of its objects is to provide a tool of this kind with means for controlling the heating of the tool, so that various degrees of heating may be readily obtained.

Another object of the invention is the provision of a tool of this character with a sliding heat unit, and means for shifting the heat unit toward the tool end of the device, so that the amount of heat transferred may be varied at will.

A further object of the invention is the provision of a tool of this general character with a tool which is connected to the body of the device by a weakened portion so that a relatively small amount of metal will connect the tool to the device, and to provide a longitudinally sliding heat unit for heating the tool, which can be shifted in various positions adjacent to the tool, so that the amount of heat transferred may be varied at will under working conditions.

A further object of the invention is the provision of a sliding electrical conductor connection between the heat unit and the body of the device, and the further provision of a handle for shifting the heat unit from the handle of the device.

With the above and other objects in view the invention consists in certain new and useful constructions, combinations and arrangements of parts, clearly described in the following specification, and fully illustrated in the drawing, in which:

Fig. 1 is a view in longitudinal section of one form of the invention.

Fig. 2 is a transverse sectional view, taken on line 2—2 of Fig. 1, looking in the direction of the arrows.

Fig. 3 is a transverse sectional view, taken on line 3—3 of Fig. 1, looking in the direction of the arrows.

Fig. 4 is a longitudinal side view, partly in section, of the modified form of the invention.

Fig. 5 is a transverse sectional view, taken on line 5—5 of Fig. 4, looking in the direction of the arrows.

Fig. 6 is a similar view, taken on line 6—6 of Fig. 4, looking in the direction of the arrows.

Referring to the drawing illustrating the practical embodiment of my invention 5 designates a handle, which may be constructed of wood, or 55 any other suitable material which is not a con-

ductor of electricity at normal voltages. This handle is formed with an axial bore or passage in which the tubular conductors 6 and 7 are inserted, and insulated from each other. The forward end of each of these conductors is split to provide spring jaws 8 and 9, and the rear ends of the two conductors provide sockets 10 and 11 to receive the prongs or pins of an electrical plug, not shown.

A tube 12 is fixed in the forward end of the handle and to this tube the metal tube 13 is fixed, by any suitable coupling means, as by the set screw 14. This tube is formed with a longitudinal slot 15, located in one side thereof, and further provided with a transverse slot 16, located near the forward end of the tube, and which thus provides a narrow heat transfer connection or neck 17, which is formed with one or more openings or perforations 18, intended to reduce the mass of metal connecting the body 20 of the tube, with the short forward section 13a.

The forward tube section 13a is provided with a tool 19, which is in the form of a finger, and which is formed by folding a strip of metal integral with the tube, upon itself, as to provide 25 a smooth forward end 20. The forward end of the short tube 13a is formed with a stop 13b.

In the tube 13 a heat unit 21 is slidably mounted, so that it will slide forwardly and about against the stop 13b. This heat unit is formed 30 with insulating cement in which the forward ends of the conductor rods 22 and 23 are secured, and in electrical connection with the opposite ends of the resistance wire used for generating the heat. The rear ends of these rods are 35 inserted in the split forward ends of the conductor tubes 6 and 7.

The connection between the rods 22 and 23 and the tubes 6 and 7 permits the sliding of the heater unit 21, without breaking the electrical 40 connection between the rods and the tubes. To produce the necessary sliding action of the heater unit, a metal rod 24 is connected to the metal tube 21a of the heater unit 21, by means of the screw 25, which works through the slot 45 15. This rod 24 is outwardly offset and slidably engages the external groove 26 of the handle 5, and is provided with a hand hold 24a at its rear end, so that the rod 24 may be readily grasped and shifted.

When the heater unit is located at the forward end of the tube 13 the maximum amount of heat is transferred to the tool 19, and by shifting the heater unit rearwardly of the extreme forward end of the tube 13, against the stop 13b thereof, 55

to various positions, different amounts of heat will be transferred to the tool 19. It is possible, therefore, to regulate the intensity of heat of the tool 19 by shifting the heater unit rearwardly or forwardly in the tube 13.

In Figs. 4, 5 and 6 I show a modified form of the invention, wherein two heater units are employed. The handle 30 carries the tube 31, on which the tube 32 is telescoped. The tool head 33 is formed on the forward end of this tube 32, and is substantially the same as that shown in Fig. 1. To the rear end portion of the slideable tube 32 a rod 34 is secured, and the rear end of this rod is provided with a latch pin 35, which is adapted to successively engage the spaced holes 36 formed on the handle. By shifting the spring pressed latch pin 35 into various longitudinal positions with reference to the handle, the tube 32 may be shifted.

Within the tube 32 the heater unit tube 37 is mounted to slide. This heater unit tube is equipped with conductor rods 38 and 39, which engage the conductor tubes 40 and 41, of the handle 30, in the same manner as described with reference to Fig. 1. This heater tube 37 is connected by the screw 42 to the rod 43, through the slot 44, which is formed in the tube 32, and the rear end of the rod 43 slides in the groove 43a formed in the handle 30.

By shifting either the tube 32 or the heater tube 37 the relation of the heater unit to the tool head 33 may be varied to regulate the heat.

In some cases an intense and rapid starting heat is desired, and for this purpose I provide another heater unit 45, which is in the form of a heater unit wound upon a metal sleeve 46, from which it is insulated. This heater unit is rigidly connected to the forward ends of the conductor rods 47 and 48, which are provided with insulating coverings, and which are mounted to slide in the groove 49 formed in the handle 30. A button handle 50 is attached to these heater rods and suitably insulated therefrom.

By shifting the heater unit 45 forwardly the temperature produced by the action of the inner heater unit 37 may be raised, so that a higher temperature can be obtained by combining the heat produced by both heater units. The heater unit 45 is provided with a suitable switch 5, for cutting the same out of action.

Having described my invention I claim as new:—

1. An electrical heating device consisting of a handle, a heat conductor connected to said handle and carrying at its outer end a finishing tool, said conductor having an intermediate portion of reduced heat conducting capacity, an electrical heating unit movable along said conductor from a position wholly at one side of said intermediate portion to the other side thereof and electrical circuit connections through said handle for said heating unit. 10

2. An electrical device consisting of a handle, a tube connected with the handle, a tube slideable on the tube and provided with a terminal tool, an electrical heater unit slideable in the second tube, means for supplying current to the heater unit in all positions, means for manually sliding the heater unit, a second heater unit slideable on the second tube, means for supplying current to the second heater unit, and means for shifting the second heater unit. 15

3. An electrically heated hand tool consisting of a handle, a tube connected to the handle, a tool head on the tube having a portion connecting the same to the tube which is considerably smaller in heat conductivity than the remainder 25 of the tube, an electric heating unit and means for mounting said unit for movement in said tube from one side of said tube portion to the other to vary the amount of heat transferred to the tool head. 30

4. An electrically heated tool, consisting of a handle, a metal tube connected to the handle, a tool head on the tube, tubular conductor members in the handle, an electrical heater element mounted to slide in the tube toward and away 35 from the tool head, conductor rods connected with said heater element and slideable in the tubular conductor members, and an additional electrical heater element slideable on the tube. 40

5. A finishing tool for furniture comprising a handle, a hollow tube rigidly connected to said handle, a flat faced finishing tool upon the outer end of said tube and rigidly supported thereby, a heating unit slideably movable along said tube and adapted to be retained in any one of a plurality 45 of adjusted positions whereby the temperature of the tool may be varied at will and an operating member connected to said heating unit extending upwardly toward the handle portion for varying the position of the heating unit. 50
